STRIP FEEDING APPARATUS

Bohumil R. Tykal, Berwyn, Ill., assignor to Western Electric Company, Incorporated, New York, N. Y., a corporation of New York

Application April 10, 1940, Serial No. 328,921

1 Claim. (Cl. 271—2.1)

This invention relates to strip feeding apparatus and more particularly to apparatus for intermittently feeding a plurality of strips simultaneously to a material working apparatus.

Considerable difficulty has been experienced in feeding a plurality of strips to a punch press designed to form a number of parts simultaneously due to the fact that the strip material from which the parts are to be made varies in thickness and, if a single feeding device is provided, slippage will occur between the thin parts and the feeding apparatus and the proper amount of material will not be fed for those strips which are slightly under size unless some means is provided for compensating for the variations in thickness of the strip material.

Attempts have been made to feed strips of material by using a soft rubber or synthetic rubber roller in association with a metallic roller driven in synchronism with the operation of the punch press. This method of feeding strip stock has not proved entirely satisfactory due to the fact that when sufficient pressure is put on the rubber roller to cause it to engage all of the strips of stock being fed into the working apparatus, the rubber roller would flatten out and not feed the same amount to each of the operating mechanisms for operating on the strips.

It is an object of the present invention to provide a simple apparatus for feeding accurately measured amounts of strips of material simultaneously to material working apparatus.

In accordance with one embodiment of the invention, a pair of cooperating feeding rollers are provided, one of these rollers being a metal feeding roller of a conventional type operated from the drive mechanism of the punch press. Cooperating with this conventional roller for imparting intermittent feeding motion to a plurality of strips of stock is a feeding roller, spring pressed into engagement with the first-mentioned roller, and comprising a drum or cylinder with a series of rings of resilient material, such as rubber or preferably synthetic rubber, encircling it and having superposed on them a series of metallic rings, one ring being provided for each rubber ring, and the rings being connected through the rubber to the drum or cylinder.

Other objects and advantages of the invention will be apparent from the following detailed description of one embodiment thereof, reference being had to the accompanying drawing, wherein

Fig. 1 is a front elevational view of a punch press designed to work on a plurality of strips of metal at a time and having a stock feeding

mechanism adapted to feed equal amounts of stock to the press for each reciprocation of the tools in the press;

Fig. 2 is a vertical sectional view on an enlarged scale, taken along the line 2—2 of Fig. 1 in the direction of the arrows and showing the construction of the feed rollers, and

Fig. 3 is a vertical sectional view taken along the line 3—3 of Fig. 2 in the direction of the arrows.

Referring now to the drawing, wherein like reference characters designate the same parts throughout the several views, particular reference being had at this time to Fig. 1, there is shown a punch press mechanism and its cooperating feed mechanism, which include a bed 4 mounted upon a suitable standard or base 5 and carrying a bolster plate 6. Mounted upon the bolster plate 6 is a suitable die block 7 for cooperation with a reciprocating punch block 8 carrying punches 9—9 and a positioning pin or guide pin 10, as well as a suitable cut-off punch 11. The punches 9, positioning pin 10 and cut-off punch 11 are shown purely as an example of the types of tools which may be used and it should be understood that various other types of tools might be provided without departing from the present invention, which is not directed to the tools per se, but rather to the feeding mechanism for feeding strips of stock 12 to the tools.

The punch block 8 is mounted upon a suitable ram 13 and is adapted to be reciprocated by a connecting rod 14, the ram 13 being guided in ways 15 and 16, as is usual in punch presses of the type illustrated herein. The connecting rod 14 has reciprocating motion imparted thereto by the usual type of crank mechanism not shown in detail but positioned behind the plate 17 and driven with a fly wheel 18. The actuating mechanism for the feeding apparatus, as is usual in punch presses of this type, is actuated by a link 19 pivotally connected to the plate 17 and transmitting power from the crank shaft of the press to the feeding apparatus. The link 19 has its lower end pivotally connected to a lever 20, which is interconnected with trunnions 21 by either a pawl and ratchet mechanism, a free wheeling type of clutch, or similar mechanism, so that upon movement of the lever 20 in a counter-clockwise direction, the trunnions 21 will be driven by the lever 20, but upon movement of the lever 20 in a clockwise direction, the lever will not move the trunnions 21. Any suitable mechanism known to the art may be utilized for accomplishing this function and the form of appa-

status shown herein is simply illustrative of one type useful in connection with the present invention.

The trunnions 21 are mounted for rotation in side plates 22 of a feeding assembly positioned on the bed 4 and designated generally by the numeral 32. Slots 23 are formed in the side plates 22 for receiving bearing blocks 24 in which trunnions 25 are journaled. The bearing blocks 24 are slideable in the slots 23 and are normally urged downwardly by pins 26 pressing against the blocks and being urged downwardly by a coiled spring 28 surrounding a rod 29 and interposed between a washer 30 and a washer 27, a nut 31 being provided for adjusting the position of the washer 30 and the lower end of the rod 28 being fixed in a top plate 33 secured to the side plates 22. The bearing blocks 24 receive trunnions 25, which extend outwardly from a feeding cylinder 36, which cooperates with a metal feed roll 37 in the feeding of the strips 12 to the operating mechanism of the punch press. Suitable gearing is provided for interconnecting the cylinder 36 and feed roll 37 so that they travel at the same speed in feeding stock. It should be noted, however, that it is not essential to drive both the cylinder 36 and the feed roll 37 since either of them may be used as an idler. The cylinder 36 has a series of groups of pockets 38 formed therein, there being four pockets 38 in each group of pockets and there being a group of pockets for each strip 12 to be fed. The pockets 38 receive pins 39, the outer ends of which are fixed in steel rings 40 so that when the cylinder 36 rotates, the steel rings 40 will be rotated with it. Interposed between the outer surface of the cylinder 36 and the inner surface of the steel rings 40, and suitably secured to the steel rings 40, are a series of cushioning members in the form of synthetic rubber rings 41, which permit the steel rings to be forced out of their normal position when a relatively thick strip is engaged by one of the rings, as shown, for example, at A and B (Fig. 2). The rings 40, which engage strips 12, slightly thinner than average, are shown at C and D and the other or average size strips 12 are shown at E and F and will also be engaged by their respective rings 40. In this manner, those rings 40 which engage the thin strips 12, although they are moved into a position eccentric of the cylinder 36, will tightly engage the strips 12 and will feed them exactly the same distance as those rings 40 which engage the thick strips and the average sized strips due to the fact that, the peripheries of all of the rings being exactly the same size, the lineal travel of the surfaces of the rings which engage the stock will be the same regardless of whether the rings happen to be engaging a relatively thick or relatively thin strip 12.

As is usual in punch presses of this type, the feed rollers which feed the parts to the press are separated by an abutment 42 fixed to the ram 13 engaging a lever 43 and moving the bearing blocks 24 upwardly with respect to the lower feed roller 37 just before the guide pin 10 strikes

the strip 12 of stock to adjust it for position under the punches 9.

A better understanding of the operation of the device will be had from the following brief description of the operation thereof. After a number of strips of stock 12 are suitably positioned between the cylinder 36 and roll 37, the punch press may be started and, in its downward stroke from the position shown, it will feed one-half the desired length of stock to the tools before the abutment 42 strikes the lever 43. Continued rotation of the fly wheel 18 will cause the ram 13 to move downwardly and the guide pin 10 will position the stock accurately and shortly thereafter the punches 9 and shear 11 will punch holes in the stock and shear one part of the stock from the main body thereof. The punching will occur during the period when the link 49 is beginning to move downwardly to the right (Fig. 1). Continued rotation of the fly wheel 18 withdraws the punches and guide pin 9 and 10, respectively, from the stock. As the ram 13 moves the last quarter of the distance in its upward travel, the crank 19 will have stopped moving downwardly to the right and will begin moving upwardly to the left (Fig. 1) and will start to feed the stock, the abutment 42 having moved away from the lever 43 and permitted the springs 28 to force the rings 40 into engagement with the stock before the rollers start to rotate. If all of the strips of stock 12 between the cylinder 36 and roll 37 are of exactly the same thickness, then all of the rings 40 will have an equal amount of eccentricity with respect to the roller 36. However, if some of the strips 12 are thick and some thin, the cushion of synthetic rubber 41 will permit the rings 40 to adjust themselves so that they will all bear against the strips of stock 12 with substantially the same pressure and since for each cycle of rotation of the cylinder 36 the peripheral surface of the rings 40 will move through exactly the same distance, the amount of stock fed by each ring 40 will be the same as that fed by all of the other rings.

Although a specific embodiment of the invention has been described hereinbefore, adaptations thereof may be made without departing from the scope of the present invention, which is to be limited only by the appended claim.

What is claimed is:

In a strip feeding apparatus, a feed roller comprising a cylindrical body member having a series of groups of radially extending pins receiving pockets formed in it, a plurality of non-resilient metallic rings surrounding said body member, annular cushioning members of resilient material surrounding the cylindrical body member and interposed between the body member and the non-resilient rings, said annular cushioning members being individual to said non-resilient rings and being of a width equal to the width of said non-resilient rings and a group of pins fixed to each of the rings and extending radially inwardly through the cushioning member and into the pockets in the body member.
